US00D532363S

(12) **United States Design Patent** (10) **Patent No.:** **US D532,363 S**
(45) **Date of Patent:** **** Nov. 21, 2006**

(54) **BATTERY**

(75) Inventor: **Yujin Morisawa**, Tokyo (JP)

(73) Assignee: **Sony Corporation**, Tokyo (JP)

(**) Term: **14 Years**

(21) Appl. No.: **29/206,271**

(22) Filed: **May 28, 2004**

(51) **LOC (8) Cl. 13-02**

(52) **U.S. Cl. D13/103**

(58) **Field of Classification Search** D13/102-106,
D13/110, 118-119, 184; 429/96-100, 163,
429/176

(57) **CLAIM**

The ornamental design for a battery, as shown.

DESCRIPTION

FIG. 1 is a perspective view of a first embodiment of a battery showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof;

FIG. 8 is a perspective view of a second embodiment of a battery showing my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.
